UNITED STATES PATENT OFFICE.

LORRIN A. MATTHEWS, OF VICTOR, IOWA.

RAIL CHAIR.

1,403,906.

Specification of Letters Patent. Patented Jan. 17, 1922.

Application filed September 21, 1921. Serial No. 502,234.

To all whom it may concern:

Be it known that I, LORRIN A. MATTHEWS, a citizen of the United States, residing at Victor, in the county of Iowa, 5 State of Iowa, have invented a new and useful Rail Chair; and I do hereby declare the following to be a full, clear, and exact description of the invention, such as will enable others skilled in the art to which it 10 appertains to make and use the same.

The invention relates to rail chairs, and has for its object to provide a device of this character particularly adapted for use in connection with dredge tracks of the 15 type where track sections are moved on their platforms and positioned in advance of each other by the dredge, as said dredge advances during its dredging operation.

A further object is to provide a rail 20 chair so constructed that the adjacent ends of abutting rails may be easily and quickly secured in the chair by removable pins, and also to provide a flared guide portion on the chair, said guide portion forming 25 means for guiding the end of a rail into abutting engagement with a rail end secured in the chair, thereby allowing platform sections having rails to be easily and quickly secured together.

With the above and other objects in view 30 the invention resides in the combination and arrangement of parts as hereinafter set forth, shown in the drawings, described and claimed, it being understood that 35 changes in the precise embodiment of the invention may be made within the scope of what is claimed without departing from the spirit of the invention.

In the drawings:—

40 Figure 1 is a top plan view of the rail chair showing the same secured to a portion of a conventional form of platform track section, of the type used in connection with dredging and excavating machinery.

Figure 2 is a side elevation of the rail chair.

Figure 3 is an end view of the rail chair looking into the flared guide end thereof.

50 Referring to the drawings, the numeral 1 designates portions of adjacent road bed sections, of the type commonly called platforms and of the type used in connection with dredging machines, wherein as the 55 machine as a whole advances rail sections are shifted for continuing the track in ad-

vance of the dredge. It has been found that when the railway sections are connected together in the usual manner with fish plates or conventional forms of chairs that a great 60 deal of time is lost in getting the rails in abutting engagement with each other. To overcome this difficulty a chair 2 is provided, which chair comprises a base 3 which may be secured to the road bed section 1 by 65 means of bolts 4. Extending upwardly from the base 2 are spaced flanges 5, between which flanges the end 6 of the rail 7 is received, and held by a removable pin 8, which pin extends through the flanges 5 70 and the web 9 of the rail 7. Flanges 5 engage the side edges of the flanges of the rail 7 and hold said rail in the rail chair. Flanges 5 are provided with inwardly extending lugs 10 which overlie the flanges of 75 the rail 7^a after said rail has been placed in the flared portion 11 of the chair and guided to its abutting position with the end of the rail 7 by the angularly disposed flanges 12 which extend upwardly from the 80 base 2 and are integrally formed with the flanges 5. It will be seen that when a track section is being placed in position in advance of another track section that the end of the rail 7^a will be guided to abutting 85 position with the end of the rail 7 and that after the rail has been so guided to position, the pin 13 is passed through an aperture in the web thereof and through notches 14 in the upper sides of the flanges 5, said pin 90 forming means whereby the end of the rail 7^a will be securely held in place. It will be seen that the rails may be easily and quickly disconnected by removing the pin 13 and consequently the road bed sections 95 may be also disconnected thereby allowing the roadbed sections to be placed in advance of each other during a dredging or excavating operation.

From the above it will be seen that a rail 100 chair is provided which is simple in construction, and one wherein the chair may be cast in a single piece, thereby allowing the device to be cheaply manufactured.

The invention having been set forth what 105 is claimed as new and useful is:

1. A rail chair comprising a base, upwardly extending parallel flanges carried by said base adjacent its ends for the reception of one end of a rail, means passing 110 through registering apertures of said parallel flanges for holding the end of said

5 rail in position, the forward ends of said parallel flanges merging into diverging extending flanges carried by the base, said diverging flanges forming guiding means for
10 5 guiding the end of a rail into position between the parallel flanges, lugs carried by the parallel flanges adjacent their inner ends and adapted to overlie the flanges of the last mentioned rail and means carried
15 10 by said parallel flanges for holding the last mentioned rail in position.

2. A rail chair comprising a base, upwardly extending flanges carried by said base, said flanges adjacent one end of the base being parallel and merging into out-

wardly extending flanges, said outwardly extending flanges forming means for guiding a rail end to a point between the parallel flanges, inwardly extending lugs carried by the flanges and adapted to overlie the rail 20 flanges and means carried by the parallel flanges for holding the adjacent ends of rails between the parallel flanges.

In testimony whereof I have signed my name to this specification in the presence 25 of two subscribing witnesses.

LORRIN A. MATTHEWS.
